Des. 203,055
Patented Nov. 30, 1965

203,055

BEVERAGE CADDY

Edward L. Robinson, 229 Wilson, Placentia, Calif.

Filed Jan. 11, 1965, Ser. No. 83,634

Term of patent 14 years

(Cl. D44—10)

FIG. 1.

FIG. 2

FIG. 3.

FIG. 4.

FIG. 5.

FIG. 1 is an isometric view of a beverage caddy showing my new design;

FIG. 2 is a front elevation thereof;

FIG. 3 is a top plan view thereof;

FIG. 4 is a bottom plan view thereof; and

FIG. 5 is a side elevation thereof.

I claim:

The ornamental design for a beverage caddy, substantially as shown.
